UNITED STATES PATENT OFFICE

JOHN S. JOHNSON, OF MILWAUKEE, WISCONSIN

HONE WHEEL

Application filed April 5, 1926. Serial No. 99,841.

This invention relates to improvements in hone wheels, particularly adapted for use in the polishing of marble blocks and the like.

Heretofore in hone wheels it has been necessary to secure the abrasive blocks to the wheel plate by means of heated shellac or other adhesive material. The objection to this form of connection will be readily appreciated as considerable time is required to 10 prepare the shellac, apply it, and then allow it to set.

It is the primary object of the present invention to provide a hone wheel in which the above objection is overcome by mechanically 15 clamping the abrasive block or blocks to the wheel plate.

A further object of the invention is to provide a hone wheel in which the abrasive block may be very quickly attached to or detached 20 from the wheel plate, and when attached it is positively and securely held in fixed position.

A further object of the invention is to provide a hone wheel for clampingly receiving an integral abrasive block, or a plurality of small 25 or sectional abrasive blocks.

A further object of the invention is to provide a hone wheel which is of very simple construction, is strong and durable, is efficient in operation, and is well adapted for the purposes described.

With the above and other objects in view the invention consists of the improved hone wheel and its parts and combinations as set forth in the claim, and all equivalents there- 30 of.

In the accompanying drawing in which the same reference characters indicate the same parts in all of the views:

Fig. 1 is a plan view of the improved hone 40 wheel, part being broken away to show details of construction;

Fig. 2 is a side view thereof, part being broken away and shown in section;

Fig. 3 is a detail view of one of the locking 45 lugs employed;

Fig. 4 is a fragmentary plan view of a slightly modified form of hone wheel and embodying the invention;

Fig. 5 is a sectional view thereof taken on 50 line 5—5 of Fig. 4; and

Fig. 6 is a perspective view of a locking lug.

Referring now more particularly to the drawings it will appear that the numeral 8 indicates a hone wheel having an annular plate portion 9 provided with a central bored hub portion 10 to receive a shaft. The underside of the plate portion is formed with a plurality of radially extending ribs 11 formed with internally threaded bores 12. The top portion of each rib, adjacent the plate portion, is provided with a rectangular recess 13 and the plate portion, above each of such recesses, contains T-shaped slots 14.

An abrasive block 15, formed of any suitable abrasive material or composition, and shaped preferably as shown in Fig. 1, is adapted for removable mounting on the plate portion of the hone wheel. Said block is a circular integral block having a plurality of sections defined by grooves or depressions 16, and the inner periphery of the block abuts 70 against an annular rib or shoulder 17 projecting from the face of the plate portion adjacent the central bore.

Locking lugs 18, shaped as shown in Fig. 3 are provided for clamping the abrasive block to the plate portion. Said lugs are formed with rectangular shank portions 19 and head portions 20 at right angles to the shanks, and the heads, below the shanks are counter-sunk 80 and formed with bolt openings 21. As shown clearly in Fig. 2 a locking lug has its shank portion inserted into each of the rectangular openings 13 and the upper portions of the heads engage the outer surface of the abrasive block to hold it firmly and removably in position. The locking lugs are clamped into adjustable position by means of bolts 22 which extend through the bolt openings 21 in 90 the heads and into the threaded bores 12.

Thus it will be seen that the improved hone wheel provides means for quickly and positively attaching an abrasive block to the wheel and when the same becomes worn it 95 may be quickly removed and replaced. Should any of the block sections split from the main block while in use said split portions will be held in position because of engagements with the lugs ad the shoulder 17. 100

The slots 14 allow dust and grindings to be brushed free of the openings 13.

A slightly modified form of the invention is illustrated in Figs. 4, 5, and 6 wherein the 5 wheel plate 9' is adapted to receive a plurality of angularly shaped abrasive blocks 15' forming the abrasive surface instead of a large integral block. For this purpose the upper surface of the plate portion is formed 10 with a plurality of spaced, angularly shaped lugs 23 between which the blocks 15' are clamped by means of locking lugs 18', shaped as shown in Fig. 6. The lugs 18' are held 15 within slots 13' in the wheel by means of bolts 22.

From the foregoing description it will be seen that the improved hone wheel is of very simple and novel construction, and is well adapted for the purposes set forth.

20 What I claim as my invention is:

A hone wheel, comprising a wheel member having a body portion formed with a plurality of spaced, radially extending T-shaped, slotted recesses, said wheel member also having 25 a plate portion, an abrasive member mounted on said plate portion, a plurality of T-shaped clamping members having their shank portions extended into said recesses and the head portions engaging the peripheral surface of the abrasive member, and bolts threaded through said clamping members and the wheel body portion to adjustably hold the clamping members in clamping position.

30 35 In testimony whereof, I affix my signature.
JOHN S. JOHNSON.
